REFLECTOR PROJECTION LAMP

Theodore O. Hall, West Los Angeles, Calif., assignor to Hall & Connolly, Inc., New York, N. Y., a corporation of New York

Application February 3, 1934, Serial No. 709,658

8 Claims. (Cl. 176—51)

This invention relates to projector lamps especially adapted for the projection of motion pictures. The high intensity flaming arc light has come into use for such lamps to a great extent on account of its high intrinsic brilliancy but complications, high cost and the heavy current used in most of such lamps have militated against its use in the smaller playhouses. One object of this invention is to devise a high intensity projection lamp of moderate current consumption and extremely simple and inexpensive design. By pointing the positive electrode away from the projector lens and employing a reflector, the quantity of light on the screen may be greatly increased. I have also simplified the construction of the standard high intensity lamp by eliminating the rotation of the positive electrode which has enabled me to greatly reduce the size of the positive electrode holder thereby decreasing the shadow cast thereby.

A further improvement accomplished by my invention is the rotation of the reflector whereby uneven heating of the same is avoided and also the bad effects of flaws in the surface of the reflector substantially reduced.

Referring to the drawings showing a preferred form of my invention,

Fig. 1 is a side elevation, partly in section, of my improved projector lamp unit with the housing omitted.

Fig. 2 is a rear elevation of the same.

Fig. 3 is a horizontal section taken through the negative holder.

Fig. 4 is a detail of the feeding means for one of the electrodes.

Fig. 5 is a section taken approximately on line 5—5 of Fig. 4.

Fig. 6 is a rear face view of the reflector rotat-

ing gear.

Fig. 7 is a vertical section taken on line 7—7 of Fig. 6.

Fig. 8 is a front view of the feed rollers for the positive electrode.

The lamp structure is shown as comprising a back or baseplate 1, to the outside of which is secured the lamp operating mechanism including the driving motor 2 and the blower 3 driven therefrom. Detachably secured to the inside of said plate is the supporting framework 4 of the lamp proper. Said framework is shown as hollow and engages at its rear end the end of the insulated tube 5 projecting from the blower so that air is discharged therefrom through the hollow framework. On top of said framework are mounted bracket 6 and bearing blocks 7 and 7', said blocks

having journalled therein a plurality of sleeves supporting the negative electrode 8. Next to said electrode is shown a split sleeve 9 which is caused to tightly grip the electrode at its forward end by inclined surfaces thereon which are engaged by the inner tapered surface of the second sleeve 10, said sleeve being threaded at its rear end in a sleeve 11 pinned to the inner sleeve 9 so that the outer sleeve may be rotated and drawn rearwardly with respect to the inner sleeve to 10 tightly clamp the electrode. The outer sleeve 10 is also shown as provided with rack teeth 12 at one side thereof with which mesh the teeth of a pinion 13 on a vertical shaft 14 for feeding the negative electrode. A striking knob 17 is 15 also shown on the outer end of said sleeve. To strike the arc, knob 17 is pushed inwardly to contact the electrodes. This winds up torsion spring 80 connecting the upper and lower parts of shaft 14 until lugs 81 and 82 on collars 83 20 and 84 contact. Upon release of the knob, the spring unwinds and draws the arc.

I show the negative electrode holder as projecting through an aperture in the center of the reflector 13'. As shown, the reflector is tightly 25 clamped at its center between a flanged nut 14' and a flanged sleeve 15 with suitable shock and heat absorbing washers 16, 16' therebetween. The sleeve 15 is shown as rotatably mounted in bracket 1' and as secured to the hub of a gear 30 17, which is rotated from a pinion 18 on shaft 19. It will, therefore, be readily apparent that the reflector may be revolved at any desired speed by rotating the shaft 19.

Instead of rotating the positive electrode, I 35 maintain the symmetry and depth of the positive crater by imparting a wabbling or rotary motion to the tip of the negative electrode. This distributes or revolves the negative flame around the crater of the positive electrode and prevents 40 unequal side burning. This may be conveniently accomplished from the mechanism which rotates the reflector. To this end I have shown the gear 17 as provided with an eccentric interior bore 20 within which is rotatably mounted the reduced 45 end 21 of an exterior non-rotating sleeve 22. Said sleeve is shown as housing the pinion 13 and is provided at its rear end with a spherical seat 23 engaging countersunk opening in the fixed upright 6. Therefore, as gear 17 is revolved it 50 will oscillate sleeve 22 about a point in the axis of electrode 8 as a center, thus oscillating the negative electrode as a whole about said center and causing the tip thereof to describe a small circle of about the diameter of the crater of the 55

positive electrode but without rotating either the negative or the positive electrode on their own axes. Thus the direction of the negative flame as well as its position is continuously changed. 5 By this means the introduction of current to both electrodes is greatly simplified.

The positive electrode 8' is shown as mounted in a hollow holder 25 in front of the negative electrode. As shown the air passing through the 10 main support 4 is allowed to emerge at suitable points 26 and 27 for cooling the negative holder and also at point 28 where baffles 29, 29' are placed to direct a current of air over the face of the reflector to cool the same and prevent 15 deposits thereon. Air also passes through the passage 30 up through the hollow positive holder 25 to cool the positive holder and electrode, air also emerging at 31 for the same purpose.

The feeding of the positive electrode is shown 20 as effected from a feed shaft 32 by means of a worm 33 meshing with wormwheel 34 which drives a large gear 35 through idler 36. Gear 35 constitutes the lower feed roller and is shown as provided with a V-shaped groove 37 for this 25 purpose. Above said electrode is shown an upper roller 38 which may be geared to the lower roller and is held clamped against the same by means of a spring 39 which exerts a pressure in a counter-clockwise direction around the pivot point 40. 30 Preferably current is introduced to the positive electrode through the feed rollers so that the usual heavy contact brushes are eliminated. In front of said rollers there is preferably placed an insulated shield 90 to prevent the arc striking back 35 to the rollers. A rearward supporting roller 42 may also be provided. For operating the feed shafts, I have shown shaft 32 as connected through universal and detachable couplings 44 to shaft 45 extending through the backplate 1. 40 Similarly the negative feed shaft 14, is shown as having a wormwheel 46 on the bottom thereof operated from a worm 47 on a shaft 48 which is connected through detachable coupling 49 to a shaft 50 journaled in said backplate. 45 Said feed shafts are preferably both operated from the same driving motor at proper speeds to maintain the crater of the positive electrode at the focus of the reflector and to maintain the proper arc length. To effect this purpose I have 50 shown roller or ball clutches 52, 53 (hereinafter referred to as roller grip type clutches) on the shafts, against both of which is shown a spring brake 78. Each clutch may comprise a cam-shaped plate 54 (Fig. 5) having a pin 55 extending outwardly therefrom through cover plate 54' and entering a slot 56 (or 56') in a reciprocated side rod 57 operated from a lever 58 pivoted at 55 and oscillated from a connecting rod 60 connecting said lever 58 and a crank pin 61 on a gear 62 rotated from the motor 2 by means such as worm 63. When pin 55 is rotated counterclockwise in Fig. 4, for instance, rollers 55 will grip the housing 53 to rotate the same. This will rotate shaft 50 through slip friction clutch 68 which is pressed against 53 by spring 67. The extent of step-by-step motion of each clutch may accurately be adjusted in infinite steps by means of threaded shafts 65 and 66 which engage respectively stops 67 and 68 on each of cover plates 54' to limit the back strokes of the plates 54. By this means the rates of feed of each electrode may be adjusted so that each is fed at the proper rate to maintain the proper position of the positive crater and the proper arc length. 70 For quick hand feeding, a knurled head 69 is pro-

vided for each feed shaft. One spring 71 may be provided for returning both ratchet feeds after actuation, the spring being shown as connected across between the two pins 55 and 55'. The upper end of lever 58 is shown as carrying a pawl 5 73 for rotating the ratchet 74 on the shaft 75, which is coupled to the shaft 19 above described for rotating the reflector and oscillating the negative tip.

In accordance with the provisions of the patent statutes, I have herein described the principle and operation of my invention, together with the apparatus which I now consider to represent the best embodiment thereof, but I desire to have it understood that the apparatus shown 15 is only illustrative and that the invention can be carried out by other means. Also, while it is designed to use the various features and elements in the combination and relations described, some of these may be altered and others omitted 20 without interfering with the more general results outlined, and the invention extends to such use.

Having described my invention, what I claim and desire to secure by Letters Patent is:

1. In a high intensity flaming arc lamp having a positive and negative electrode, of a stationary holder for the positive electrode and a revolvable holder for the negative electrode for bodily revolving the tip thereof so as to describe a small 30 circle in front of the crater of the positive electrode and concentric with the major axis or core of the same, whereby a symmetrical crater is maintained.

2. In a reflector type projector lamp, a pair 35 of electrode holders, a reflector, means for rotatably mounting the same, and means for continuously rotating the same, whereby uniform cooling is secured and the ill effects of imperfections in the reflector surface overcome.

3. In a reflector type projector lamp, a pair of electrode holders, a reflector, means for rotatably mounting the same, means for continuously rotating the same, and means actuated by rotation of said reflector for causing the tip of one of the electrodes to describe a closed figure in front of the other electrode.

4. In an arc projector lamp, an electric motor for feeding both electrodes, a feeding shaft for each electrode, and variable speed means connecting said motor and each of said feed shafts comprising a pair of roller grip type clutches, a slide rod reciprocated by said motor, and having a lost motion connection with each clutch, and independent means for varying the amount of rotation imparted to each feed shaft per stroke of said rod.

5. A variable speed feed for an electrode of an arc lamp comprising a source of power, a feed shaft, a roller grip type clutch connecting to said shaft to rotate the same step-by-step, a member reciprocated by said power source, having a lost motion connection to said power source, a spring for returning said clutch after each stroke, and an adjustable stop to vary the effective stroke of the clutch in infinite steps.

6. In a reflector arc lamp, an electrode holder comprising a fixed support, a sleeve normally gripping the electrode, means for advancing said sleeve for feeding the electrode, a rotatable element around said sleeve journaled in said support and having an eccentric aperture therein, a reflector secured to and insulated from said element to be rotated thereby, and an intermedi-

ate sleeve journalled at one end in said element and having a universal mounting at a remote point in said fixed support, whereby rotation of said element wobbles the inner sleeve and the tip of the electrode.

5. 7. In a reflector type projector lamp, a negative electrode holder, a reflector rotatably mounted thereon and having a central aperture through which the electrode normally projects, means for 10 insulating the reflector from its mounting, and

means for circulating air over the reflector for cooling the same.

8. In a reflector type projector lamp, an electrode holder comprising a fixed support, a sleeve journalled therein, a reflector having a central aperture therein clamped in said sleeve, means for continuously revolving the sleeve and reflector, and means for feeding an electrode through said sleeve.

THEODORE O. HALL. 10
